LIGHTING FIXTURE

Howard A. Daum, Hanover, Pa.
(P.O. Box 128, Littlestown, Pa.)

Filed May 1, 1963, Ser. No. 74,705

Term of patent 14 years

(Cl. D48—31)

FIG. 1 is a front elevation of a lighting fixture, showing my new design, with the standard broken away in part to indicate indeterminate length.

FIG. 2 is a top plan view thereof; and

FIG. 3 is a side view thereof.

The dominant features of my design reside in the full line portions of the drawings.

The undisclosed rear is the same in appearance as the front shown in FIG. 1.

I claim:

The ornamental design for a lighting fixture, substantially as shown and described.
